UNITED STATES PATENT OFFICE

WILLIAM FRANCIS TEDHAM, OF LONDON, ENGLAND, ASSIGNOR TO VICTOR TALKING MACHINE COMPANY, A CORPORATION OF NEW JERSEY

THERMIONIC AMPLIFIER FOR USE IN CONJUNCTION WITH PHOTO-ELECTRIC DEVICES

Application filed June 24, 1930, Serial No. 463,419, and in Great Britain July 3, 1929.

The present invention relates to thermionic amplifiers for use in conjunction with photo-electric devices.

It is an object of the present invention to improve the frequency response characteristic of apparatus of this kind more particularly at the higher acoustic frequencies.

According to the present invention in a thermionic amplifier having a photo-electric device arranged in the input circuit thereof, a choke coil is arranged so as to be effectively in series with the oscillations derived from the photo-electric device. Thus the choke may be arranged in series between the photo-electric device and the grid circuit of a thermionic valve, or in addition to or in place of this choke, a choke may be disposed in series between the anode circuit of the first valve and the grid circuit of the second, or 20 in a similar position in some later stage of the amplifier.

It has been found that with this arrangement the overall frequency-response characteristic of the photo-electric device and the amplifier is improved.

The invention will be described by way of example with reference to the accompanying drawing in which,

Fig. 1 is the circuit diagram of a thermionic amplifier embodying the invention;

Fig. 2 shows a modification of the invention as applied to the circuit of Fig. 1, and

Fig. 3 is a diagram showing the type of response characteristics obtained with the circuit arrangements of Figs. 1 and 2.

In the following description suitable values are given for various components but these must not be taken as limiting the scope 40 of the invention.

Referring to Fig. 1 a photo-electric cell 1 is shunted by a resistance 2 of 0.5 megohms and one terminal of the photo-electric cell is connected to the filament of a thermionic valve 3. The other terminal of the cell is connected, on the one hand, through a resistance 4 of 0.5 megohms to the positive terminal of a high tension source, of, for example, 200 volts, and, on the other hand, through a condenser 5 of 0.2 microfarads and an inductance

such as a choke coil 9 in series to the grid of the thermionic valve 3. The grid is also connected through a grid leak 6 of 0.5 megohms to a point at suitable negative potential with respect to the filament. The 55 anode of the valve 3 is connected to a positive terminal of the above mentioned high tension source through a choke coil 7, the negative terminal of this source being connected to the filament of the valve. The 60 anode of the valve is connected through a condenser 11 and an inductance such as a choke coil 10, to the input circuit of a second valve 8. Any desired number of stages of 65 amplification may of course be added.

The inductance or choke 9 may be of 0.6 henries and is connected in series between the photo-electric cell and the grid of the valve 3. In addition to as shown or in place of this choke, the choke 10 may be disposed in 70 series between the anode circuit of the first valve and the grid circuit of the second or in a similar position in some later stage of the amplifier. For this purpose the anode of the valve 3 may be connected to the grid 75 of the valve 8 through the condenser 11 and the choke 10 after the manner of condenser 5 and choke 9, in series. The choke coil 9 constitutes with the tube capacity a series resonant circuit. This arrangement causes 80 the building up of the high frequency end of the response characteristic.

In some cases it has been found desirable to include in shunt across the grid circuit of the second valve a filter circuit comprising 85 a condenser 12, Fig. 2, of 0.0005 microfarads in parallel with a choke 13 of 1.75 henries in series with a resistance 14 of 20,000 ohms.

In Fig. 3, curves A, B and C show the 90 order of the overall response at different frequencies that has been obtained with the arrangements shown in Figs. 1, 2 and 3 respectively, the same photo-electric device being used in each case. It is evident from 95 these curves that there is an improvement in the overall response at the higher frequencies with the arrangements shown in Figs. 2 and 3.

I claim:

1. In an amplifying system for photo-

electric currents, a light sensitive cell, a thermionic relay, means for coupling said cell to the input of said relay, and a choke coil in series between said cell and said input whereby the frequency response characteristic is accentuated for higher audio frequency.

2. In an amplifier for photo-electric currents as set forth in claim 1 characterized in that the output circuit of said relay comprises the combination of an audio frequency choke coil and resistor in series and a condenser in shunt with said series combination.

15 In testimony whereof I have signed my name to this specification.

WILLIAM FRANCIS TEDHAM.
